UNITED STATES PATENT OFFICE.

FRITZ KOCH, OF ST. PAUL, MINNESOTA.

LOAD-MOVING APPARATUS.

No. 882,894.

Specification of Letters Patent. Patented March 24, 1908.

Application filed March 16, 1907. Serial No. 362,698.

To all whom it may concern:

Be it known that I, FRITZ KOCH, a citizen of the United States, residing at St. Paul, in the county of Ramsey and State of Minnesota, have invented certain new and useful Improvements in Load-Moving Apparatus, of which the following is a specification.

My invention relates to improvements in load-moving apparatus designed particularly for moving heavy machines such as derricks and steam shovels, but adapted for use with any load-supporting frame carrying a shaft and power to turn it, the object of the invention being to provide simple and efficient means for lifting and moving a load-carrying frame by the use of its own power.

To that end the invention consists in the construction, combination and arrangement of parts hereinafter described and claimed.

20 In the accompanying drawings forming part of this specification, Figure 1 is a perspective view of the invention applied to a shaft-carrying frame, the shaft-actuating means being omitted for the sake of clearness. Figs. 2 and 3 are front and side views, respectively, of a slightly modified construction of the eccentric lifting pin and web. Fig. 4 is a diagrammatic side view of the frame and carriage showing the same in normal position, both resting upon the ground. Fig. 5 is a similar view showing the frame in up-raised position; and Fig. 6 is a similar view, but with the carriage in up-lifted position, and showing means for actuating the shafts of the frame. For the sake of clearness and simplicity I have shown the invention applied to a simple frame A carrying an engine B, but it will be understood that the invention is applicable to any sort of frame, 40 whether part of a machine or not, which carries a driven shaft and means to drive it.

As shown in the drawings, the frame has two shafts 2 supported in bearings 3 upon the frame and carrying at each end a wheel 4. 45 Upon the outside of each wheel is detachably secured, by bolts 5 or otherwise, a plate or disk 6 carrying a lifting pin 7 arranged eccentrically to the shaft 2 and parallel therewith. The web between the shaft and pin thus constitutes a crank, and for convenience the pin 7 may be called a crank-pin. In Figs. 2 and 3 the pin and plate are shown as a steel casting with raised web 8 extended beyond the tread of the wheel.

50 55 Coöoperating with the supporting frame A is a skeleton carriage C of sufficiently greater

length and width than the frame to permit the frame to work within it. Arranged upon the sides of the carriage in position to receive the eccentric lifting pins 7 are skeleton bearing-frames 9 having at top and bottom interior bearings 10 and 11, respectively, with preferably divergent sides for the lifting pin 7. In order that the frame and carriage may be alternately lifted as hereinafter explained, 60 the bearings are spaced apart a distance less than twice the throw or radius of the crank. It will be observed that the frame A extends down below the shafts 2 to form a supporting base 12 to bear upon the ground and enable the carriage C to be lifted upon it, and that the lower bearing 11 of the frame 9 is positioned at such height that the lifting pin 7 will stand out of vertical alinement with the shaft 2, when the frame and carriage are 70 at rest upon the ground, as shown in Fig. 4.

The shaft 2 may be driven from the engine through the medium of any appropriate mechanism, such as the gears 13 and 14 carried, respectively, by the drive shaft 15 of the engine and one of the shafts 2, these gears meshing with an intermediate gear 16. The shafts 2 may be operatively connected, as for instance by the sprocket wheels 17 and chain 18, or such connection may be dispensed 80 with, one only of the shafts being driven.

It will be observed that the wheels 4 shown in the drawings have of themselves no function except to form a crank connection between the shaft and lifting pin or 90 crank-pin. I have shown this, however, as my preferred form of crank because such wheels are usually to be found upon the heavy machines for which my invention is particularly adapted, and they can be readily 95 used as cranks by bolting to them a pin-carrying disk such as is shown in Figs. 1, 2 and 3. After the machine has been moved to the desired place the disks may be removed and used on other machines. The 100 construction of the carriage as here shown, with the side bars arranged outside of the wheels of the frame, makes it particularly well adapted for use upon a steam shovel or other heavy machine, because the side bars 105 form a wide base for the machine to rest upon and give it more stability than if it rested simply upon its own wheels. The side bars thus serve to take the place of jacks, which are commonly used upon such machines to 110 take up the side thrust and to steady them in heavy work.

In operation, when the carriage and frame are at rest they will assume the positions shown in Fig. 4, both carriage and frame resting upon the ground. When the shaft 2 is turned right-handedly the pin 7 will be thrust against the lower bearing 11 and force the shaft and frame to rise up and move forwardly around the pin in the arc of a circle of which the pin is the center, as shown 10 in Fig. 5, until the frame descends with its shaft on the other side of the pin, the distance of its forward travel depending upon the distance between the bearings and the length of the crank. As the shaft continues 15 to revolve the pin will be turned until it lodges against the upper bearing 10, when it will lift the carriage and move it circularly forward, as shown in Fig. 6, until it descends again with the pin on the other or forward 20 side of the shaft. By continuing this alternate lifting and moving of frame and carriage the machine will be made to "walk" ahead by its own power until it reaches the desired destination.

25 It will be evident that where only the forward shaft 2 is driven, only the forward end of the frame and carriage will be lifted and moved in the manner described, the other end being merely dragged along the ground.

30 Changes may be made in the details of the device without departing from the principle of the invention, the scope of which is defined in the claims.

I claim as my invention:

35 1. An apparatus of the character described, comprising a carriage having side rails, a frame provided with a horizontally disposed rotatable shaft, and coöperating means on said shaft and on the side rails of 40 the carriage for causing both the frame and carriage to be alternately raised bodily from the ground and moved forwardly as the shaft revolves; substantially as described.

45 2. An apparatus of the character described, comprising a frame provided with a horizontally disposed rotatable shaft, lifting members connected to said shaft and disposed eccentrically thereto, and a carriage provided with separated upper and lower 50 bearing surfaces that are adapted to be engaged by said lifting members to cause the carriage and frame to be alternately raised bodily from the ground and moved forwardly; substantially as described.

55 3. An apparatus of the character described, comprising a frame provided with supporting members that are adapted to rest on the ground, a carriage which rests on the ground, a rotatable shaft carried by said 60 frame and provided with eccentrically disposed lifting members, and bearing surfaces

on the carriage coöperating with said lifting members for causing the frame and carriage to be alternately raised from the ground and moved forwardly as the shaft revolves; substantially as described. 65

4. The combination, with a frame having a shaft and means for turning it, of lifting pins eccentrically connected with the shaft, and a carriage having side rails that are provided with upper and lower bearing surfaces that are engaged by said pins as the shaft revolves to alternately lift the frame and carriage away from the ground and move them forwardly; substantially as described. 70

5. In combination, a frame, a shaft rotatably supported by the frame and means to turn it, a crank and crank-pin carried by the shaft at each end thereof, a skeleton carriage coöperating with the frame, and a bearing frame on each side of the carriage in position to receive the crank-pin, the bearing frame having upper and lower interior bearings in position to be alternately engaged by the pin in its revolution. 80

6. In combination, a frame, a shaft rotatably supported by the frame and means for turning it, a lifting pin eccentrically secured to the shaft at each end thereof, a skeleton carriage coöperating with the frame, and a pair of oppositely disposed upper and lower bearings mounted upon each side of the carriage in position to be alternately engaged by the lifting pin in its revolution, the opposing faces of the bearings having oppositely divergent sides. 85

7. The combination, with a frame having a shaft and means for turning it, of a crank and crank-pin carried by the shaft at each end thereof, a skeleton carriage coöperating with the frame, and oppositely disposed upper and lower bearings mounted upon the carriage at each side thereof in position to be alternately engaged by the crank-pin, the distance between the bearings being less than twice the length of the crank. 100

8. In combination, a frame having a shaft and means for turning it, a pair of wheels carried by the shaft, a disk detachably secured upon the side of each wheel, a pin carried by the disk eccentrically to the shaft, and a skeleton carriage coöperating with the shaft and having at each side a pair of oppositely disposed bearings in position to be alternately engaged by the pin in its revolution. 110

In testimony whereof I affix my signature in presence of two witnesses.

FRITZ KOCH.
